UNITED STATES PATENT OFFICE.

HENRY H. LOCKWOOD, OF OLEAN, NEW YORK.

VEHICLE-SHAFTS.

SPECIFICATION forming part of Letters Patent No. 450,167, dated April 14, 1891.

Application filed November 3, 1890. Serial No. 370,159. (No model.)

To all whom it may concern:

Be it known that I, HENRY H. LOCKWOOD, a citizen of the United States, residing at Olean, in the county of Cattaraugus and State 5 of New York, have invented certain new and useful Improvements in Adjustable Shafts for Vehicles; and I do hereby declare the following to be a full, clear, and exact description of the invention, such as will enable others skilled in the art to which it appertains to make and use the same.

Figure 1 is a side view. Fig. 2 is a vertical longitudinal section of Fig. 1. Fig. 3 is a bottom view of the knuckle, and Fig. 4 a side view thereof.

This invention relates to improvements in vehicle-shafts, more particularly to shafts which are to be used on two-wheeled vehicles, and which shafts are made in two parts adjustable vertically on each other to be adapted to animals of different heights.

The invention consists in the construction hereinafter set forth.

In the annexed drawings, the letter A represents the inner portion or part of the shaft which is fastened to the vehicle and has the spring-hangers a' , a detailed description of which hangers is not necessary, as they are no part of the present invention. The front 20 end of this portion A has the knuckle part B of the joint between the two parts of the shaft. This part B is slipped onto the wooden piece a^2 , the latter fitting into the socket b . The part B has the two curved shoulders $b' b'$, struck from the hole b^2 . Projecting outwardly 30 from these shoulders is the stem b^3 , in which is the hole b^3 , and this stem b^3 has at its end

the barrel C. This is cylindrical in shape, has a rounded surface, and is longer transversely. Fitted to this portion A is the other 40 portion D of the shaft. This has at its lower end d a socket E for the knuckle B. This socket has rounded cheek-pieces e, to fit the curved shoulders $b' b'$, and the stem b^3 comes between these cheek-pieces. In this socket 45 is put the two set-screws F F, and when the parts are together these set-screws bear on the barrel C. A brace-rod G is secured to the two parts, and is adjustable at the end g by the slotted plate and screw H. A bolt passes 50 through the cheek-pieces e and the stem b^3 , holding the parts together. This forms a shaft in two parts hinged together and adjustable. By turning the set-screws F F the two parts can be properly set at any desired angle. The barrel C being curved, the set-screws bind firmly on it in whatever position it is set.

Having thus described my invention, what I claim is—

1. A shaft composed of two parts, one having a knuckle and the other a socket, in combination with set-screws in the socketed part and bearing on the knuckle, as set forth.
2. The combination of the part A, having the knuckle B with the barrel C, and the part D, having the socket E and the set-screws F F, as set forth.

In testimony whereof I affix my signature in presence of two witnesses.

HENRY H. LOCKWOOD.
